[57] **CLAIM**

The ornamental design for a combined diet control board and diet kit, as shown and described.

DESCRIPTION

FIG. 1 is a front elevational view of a combined diet control board showing my new design;

FIG. 2 is a front elevational, shown in an enlarged scale for clarity of illustration, of a menu card which can be used with the diet control board of FIG. 1;

FIG. 3 is a front elevational view, shown in an enlarged scale for clarity of illustration, of a breakfast meal card which can be used with the diet control board of FIG. 1;

FIG. 4 is a front elevational view, shown in an enlarged scale for clarity of illustration, of a lunch meal card which can be used with the diet control board of FIG. 1;

FIG. 5 is a front elevational view, shown in an enlarged scale for clarity of illustration, of a dinner meal card which can be used with the diet control board of FIG. 1;

FIG. 6 is a front elevational view, shown in an enlarged scale for clarity of illustration, of the snack meal card which can be used with the diet control board of FIG. 1;

FIG. 7 is a side elevational view, shown in an enlarged scale for clarity of illustration, of a food item piece for use in the diet control kit;

FIG. 8 is a top plan view of FIG. 7;

FIG. 9 is a top perspective view of FIG. 7;

FIG. 10 is a bottom perspective view of FIG. 7; and,

FIG. 11 is perspective view of the diet control board of FIG. 1; without diet cards; shown in an enlarged scale for clarity of illustration.

The rear of the board is unornamented.
